Primary Examiner — Darlington Ly*Assistant Examiner* — Jeremy Koenig(74) *Attorney, Agent, or Firm* — Wood Herron & Evans LLP(57) **CLAIM**

The ornamental design for a wheel, as shown and described.

DESCRIPTION

FIG. 1 is a front right perspective view of a wheel according to the present invention;

FIG. 2 is a front elevation view of the wheel shown in FIG. 1; and,

FIG. 3 is a left side elevation view thereof, the right side elevation view being a mirror image thereof.

The broken lines depict portions of the wheel that form no part of the claimed design.
